UNITED STATES PATENT OFFICE.

HARRY S. HART, OF CHICAGO, ILLINOIS.

DUMP-CAR.

1,282,227.

Specification of Letters Patent. Patented Oct. 22, 1918.

Application filed July 28, 1918. Serial No. 246,314.

To all whom it may concern:

Be it known that I, HARRY S. HART, a citizen of the United States, residing at Chicago, in the county of Cook and State of Illinois, have invented certain new and useful Improvements in Dump-Cars, of which the following is a specification.

This invention relates to freight cars of the type commonly known as hopper cars, which are used very largely for the transportation of coal or like dumpable material, and has among its objects the improvement of this type of car in a manner to greatly increase the load carrying capacity of the car without changing its overall dimensions, and to provide such a car from which the load may be more quickly discharged with a minimum amount of labor, the car being practically self clearing.

With these and other objects, which hereinafter will be pointed out, the invention consists of the combinations and details described in the following specification and claims.

The invention is illustrated on the accompanying sheets of drawings, in which—

Figure 1 is a fragmentary side elevation of a dump car constructed in accordance with my invention.

Fig. 2 is a longitudinal sectional view of the same.

Fig. 3 is a transverse sectional view of the dump car taken intermediate the trucks.

Fig. 4 is a transverse sectional view of the dump car taken over the trucks, and

Fig. 5 is a fragmentary plan view of the dump car.

It has been customary to build hopper cars for the transportation of coal, and like commodities, having inclined end portions for the trucks discharging the load through the center of the car by means of cross hoppers or longitudinal hoppers provided with suitable doors. These prior constructions are well known and require no particular description for an understanding thereof. Owing to the location of the inclined end portions over the trucks, those portions of the cars at the ends are largely useless for load carrying, so that any attempt to increase the capacity of these cars necessarily has been by lengthening the car or by increasing its height, while the discharge of the load through the car hoppers is difficult, even where special unloading stations are provided owing to the necessarily restricted

door opening provided in the cross hoppers. While longitudinal hoppers also have been provided in cars of this type for discharging the load at the sides in a manner to make the unloading easier, attempts to apply this principle to the car have resulted in a greatly decreased load carrying capacity.

By my present invention I overcome the difficulties heretofore experienced in this type of car, making it possible to carry in the car of the same length a greatly increased load, and at the same time making it possible to discharge the load at a greatly reduced expenditure of time and labor.

The body 10 of this dump car, which is carried upon trucks including wheels 11 at each end of car, comprises sides 12, ends 13, and a floor 14.

The floor over the trucks consists of downwardly and outwardly sloping stationary portions 18 extending from a point adjacent and over the center sill 20 toward the sides of the car. The floor, intermediate the trucks, includes pivotally mounted doors 21, which extend downwardly and inwardly with respect to the sides 12 of the car to a point adjacent and under the center sill 20, said doors meeting along the longitudinal center of the car. These doors 21 are pivoted at their upper ends adjacent the lower ends of shedding members 22, which extend between the sides proper of the car and the doors 21. In order that the car may be self clearing in unloading, I have shown in the present embodiment of my invention the stationary floor sections 18 over the trucks extending upwardly to a point over the center sill, so as to form an A-shaped apex 15 as a continuation of the floor sections. The upper and lower floor sections at the ends and intermediate point of the car respectively, may be connected by floor members 17 sloping downwardly toward the center of the car. Suitable means may be provided for closing the space between the outer edges of the sloping floor sections 18 over the trucks and the sides 12 of the car, through which space the load over the trucks is dumped. In the present embodiment of my invention I have shown side dump doors 19, which are pivotally connected at the lower edges of the sides 12, and extend downwardly and inwardly with respect to the center of the car to meet the outer edges of the A-shaped floor portions 18. Any suitable operating mechanism may be provided

for operating the dump doors 19. Likewise, any suitable operating mechanism may be employed for operating the dump doors 21; for instance, the operating mechanism 5 shown in the Seaberg Patent No. 1,044,265, granted November 12, 1912.

By thus providing a car having stationary floor portions over the trucks, and with the downwardly and inwardly extending floor 10 portion intermediate the trucks, including dump doors, I am enabled to provide a hopper car, the carrying capacity of which is greatly increased for any given length, width and height, at the same time making 15 the car self cleaning, owing to the arrangement of the inclined surfaces in the car in reference to the dumping doors.

It will be noted that each of the floor portions of the car over the trucks is A-shaped, 20 the apex being over the center sill and the floor portion intermediate the truck is of inverted A-shape, with the apex below the center sill.

The dumping means at the ends of the 25 car over the trucks is at a higher level than the dumping means intermediate the trucks, and the load over the trucks is dumped outwardly and the load intermediate the trucks is dumped inwardly.

30 It is my intention to cover all modifications of the invention falling within the spirit and scope of the following claims.

What I claim is:

1. A car having side and end portions, a 35 stationary floor extending over the trucks at each end and composed of fixed portions sloping downwardly and outwardly from the center sill toward the sides of the car, the floor intermediate the trucks being composed of doors extending downwardly and 40 inwardly from the sides of the car toward the center of the car, and doors connecting the sides of the car with the floor portions over the trucks.

45 2. A car having side and end portions, a stationary floor extending over the trucks at each end and composed of fixed portions sloping downwardly and outwardly from the center sill toward the sides of the car, the floor intermediate the trucks being composed of doors extending downwardly 50

and inwardly toward the center of the car, there being shedding portions connecting the sides of the car with said doors, and doors connecting the sides of the car with 55 the floor portions over the trucks.

3. A car having side and end portions and a center sill, A-shaped floor portions over the trucks of the car, having their apices over the center sill, and an inverted A-shaped floor 60 portion intermediate the trucks having its apex below the center sill.

4. A car having side and end portions and a center sill, A-shaped floor portions over the trucks of the car, the apices being over 65 the center sill, an inverted A-shaped floor portion intermediate the trucks having its apex below the center sill, said intermediate floor portion including shedding portions extending downwardly and inwardly from 70 the sides of the car and doors extending in the same direction from the edge of said shedding portions, and doors connecting the lower edges of the A-shaped portions over the trucks with the sides of the car. 75

5. A car of the class described having sides, ends and a floor, the floor portion over the trucks being permanently A-shaped and adapted to discharge the load outwardly toward the sides of the car, the floor between 80 the trucks comprising doors extending inwardly from the sides toward the center of the car.

6. A car of the class described having sides, ends and a floor, the floor portion over 85 the trucks being permanently A-shaped and adapted to discharge the load outwardly toward the sides of the car, the floor between the trucks being at a lower level than the portion over the trucks and adapted to be 90 operated to discharge the load.

7. In a car of the class described having sides, ends and a floor, the floor portion over the trucks being permanently A-shaped and adapted to discharge the load outwardly 95 toward the sides of the car, the floor between the trucks being at a lower level than the portion over the trucks and arranged to discharge the load toward the center of the car.

Signed at Chicago, Illinois, this 23d day 100 of July, 1918.

HARRY S. HART.
